UNITED STATES PATENT OFFICE.

HERMANN MARCUS, OF COLOGNE, GERMANY.

APPARATUS FOR CONVEYING MATERIAL.

SPECIFICATION forming part of Letters Patent No. 782,677, dated February 14, 1905.

Application filed August 7, 1902. Serial No. 118,832.

To all whom it may concern:

Be it known that I, HERMANN MARCUS, engineer, a subject of the King of Prussia, Emperor of Germany, residing at 32 Karolinger-ring, Cologne, in the Kingdom of Prussia, Germany, have invented certain new and useful Improvements in Reciprocating Conveyers, of which the following is a full, clear, and exact description.

10 The present invention relates to improvements in apparatus for conveying material, and relates more particularly to certain improvements in the apparatus described in my prior application filed September 28, 1900, 15 Serial No. 31,399, wherein straight motion-guides are employed for guiding conveyer-troughs, and it is therein proposed to substitute for the joint-rods spirally-coiled springs. For special purposes it is advisable to provide 20 rigid connections in place of the flexible connections and to do so by arranging frames having rockers for the races to roll on, so that flexible elements of the kind above referred to are then employed only to the extent and 25 in the form as rendered necessary by circumstances. To this end the rockers are so formed as to enable them to travel along the races, and preferably this form will be circular with a radius which is situated either at the point 30 of support or within or outside the frame or triangle that carries the rockers. Accordingly the shape of the races will therefore be plain or of a concavely or convexly curved form. In some cases it is necessary to secure the 35 position of the rockers relatively to the race in order to obviate shifting of the same. For this purpose safety devices are employed—such, for example, as teeth, bolts, buffers, or straps or belts—which serve to determine the 40 position of the rocker relatively to the race during the to-and-fro motion of the trough.

In the accompanying drawings, which illustrate this improvement, Figures 1 and 2 are views in side elevation and transverse section, 45 respectively, of a suspension device with a plane race. Figs. 3 and 4 show side elevations of a similar suspension device with a concave race and with a convex race, respectively. Fig. 5 shows a side elevation of a modification

of Fig. 3. Figs. 6 and 7 show a side elevation and transverse section, respectively, of a modification of Figs. 1 and 2. Fig. 8 shows a detail side elevation of a modification of the point of support according to Fig. 1. Figs. 9 and 10 are views in side elevation and transverse section, respectively, of a further modification of the arrangement shown in Figs. 1 and 2.

In the modification shown in Figs. 1 and 2 the rocker a^2 is carried by the frame a . It 60 supports the race k of the trough f and is constituted by an arc of a circle having its center at the point of support. The race k has a plane surface, and consequently the trough will move to and fro in a rectilinear manner. The race k may also be made with a curved surface, so that the trough in such a case would describe a rocking movement in its to-and-fro motion. If the radius with which the arc of the circle of the rocker a^2 is struck is made smaller than that for the rocking movement, then the race k must be curved 65 concavely, as shown in Fig. 3, if the trough is to be guided in a rectilinear manner. If, on the contrary, the said radius is made larger 70 than the radius of the rocking motion, then the race k must be made convex, as shown in Figs. 4 and 5, if the guidance is to be rectilinear. In order to prevent shifting of the rocker 75 relatively to the race, so that the mutually contacting surfaces shall simply roll on each other, then it is necessary to secure their positions relatively to each other, and for this purpose various hereinafter-described means 80 may be employed. The means for securing same in the construction shown in Figs. 1 and 2 consists of a tooth l , which is removably fixed to the rocker a^2 and which is guided between two stops m , that are fastened to the race k . The stops m are also preferably made 85 removable, so that when any one part has become much worn it can be readily replaced by another. The arrangement may, of course, also be reversed—that is to say, the tooth l may be fixed to the race k , while the stops m are 90 fixed on the rocker a^2 . Instead of this tooth with the stops the race k may be formed as 95 shown in Fig. 3—that is to say, so that it em-

braces with its parts k' the rocker a^2 on both sides, and thereby provides the necessary securing means.

In the arrangement shown in Fig. 4 the securing means consists of two straps or belts n' and n^2 , which cross each other and are fastened at one end to the race k and at the other end to the rocker a^2 . In the rolling movement of the rocker a^2 over the race k the belts n' and n^2 are wound on and off.

A further modification of the securing means is shown in Fig. 5. In this case the rocker and race are inverted and a fixed wall o is arranged on the race k , while on the rocker a^2 there are provided elastic buffers or springs p , between which the fixed wall o is located. The arrangement may also be reversed—namely, the fixed wall o may be provided on the rocker a^2 , while the buffers or springs p are arranged on the race k .

Instead of the tooth l employed in Fig. 1 there may also be used a bolt q , which is connected to the rocker a^2 and is guided in a slot r in the race k , or vice versa, which is fixed 25 to the race k and is guided in a slot in the rocker, Figs. 6 and 7.

Hitherto instead of the spiral springs proposed in application filed September 28, 1900, Serial No. 31,399, there have been employed 30 flexible elements—such as leaf-springs, ropes, belts, or straps—which wind on and off curved bearings. Figs. 1 and 3 show for the sake of explanation flexible elements of this kind with the adjacent curved bearings, and in this 35 case the point of support for the part a' that carries the rocker is constructed in accordance therewith. For this purpose either, as shown in Fig. 1, the part a' of the frame a , that carries the rocker a^2 , is clamped in between the spring 40 curved bearings b of the supporting-block c , so that these curved bearings are wound or roll on and off in the reciprocating movement, or a leaf-spring or a strap or belt d is fixed at one end, between the bearings e , and the other end 45 between the triangle a , as shown in Fig. 3, and then those parts which receive the leaf-spring or the belt d are formed as curved bearings b . In many cases this might be a disadvantage, mainly in those cases where dusty materials 50 are conveyed by the trough. In this case the dust and dirt will soon cover the curved bearings, and thus cause a false movement. In order to prevent this, the points of support in the arrangements shown in Figs. 4 and 5 are 55 constituted by knife-edges s with knife-edge caps or covers t , so that the caps t always cover

up the knife-edges s , and thus render it impossible for dust to lodge. Also in place of the knife-edges s there might be employed a slotted plate a^3 , as shown in Fig. 8, which moves 60 on a concaved rocker u , the arrangement being such that the curved surface is covered over by a bent piece or strap y , passed through the slotted plate, and is thus protected from dust.

In the mode of construction illustrated in 65 Figs. 9 and 10, in which the rocker a^2 is secured against the race by means of a tooth l engaging with stops m , corresponding with Fig. 1, it is best that the knife-edge cap t should form an integral part of frame a across 70 the conveyer, and the cap can even, as shown in the section, Fig. 10, join two opposite frames a , as the said cap covers the knife-edge s along its whole length. The said knife-edge s in Fig. 9 is held by means of hoops w , fastened 75 to the channel-irons x , and as the cap t passes under the channel-irons it is impossible for the said cap to spring away from the knife-edge.

What I claim, and desire to secure by Letters Patent, is—

1. A reciprocating conveyer comprising frames each having a rocker, races working in conjunction with the rocker, and supports for the frames. 85

2. A reciprocating conveyer comprising frames each having a rocker, races working in conjunction with the rockers, means for connecting the rockers and races, and supports for the frames. 90

3. A reciprocating conveyer comprising frames each having a rocker, races working in conjunction with the rockers, tooth and stops connecting the rockers and races, and supports for the frames. 95

4. A reciprocating conveyer comprising frames each having a rocker, races working in conjunction with the rockers, supports for the frames, and plates and curve bearings between the supports and the frames. 100

5. A reciprocating conveyer comprising frames each having a rocker, races working in conjunction with the rockers, supports for the frames, and spring-plates and spring-curved bearings between the supports and the frames. 105

In witness whereof I subscribe my signature in presence of two witnesses.

HERMANN MARCUS.
